WHIPPER

Harry L. Stiles, Chicago, Ill., assignor to Chicago
Electric Manufacturing Company, Chicago, Ill.,
a corporation of Illinois

Application July 9, 1948, Serial No. 147,451

Term of patent 14 years

(Cl. D44—1)

To all whom it may concern:

Be it known that I, Harry L. Stiles, a citizen of the United States, residing in Chicago, Cook County, State of Illinois, have invented a new, original, and ornamental Design for a Whipper, of which the following is a specification, reference being had to the accompanying drawing, forming a part thereof.

Fig. 1 is a front elevational view of a whipper, showing my design;

Fig. 2 is a side elevational view of the whipper; and

Fig. 3 is a plan view of the whipper.

The dominating features of my design reside in the portions illustrated in solid lines.

I claim:

The ornamental design for a whipper, as shown and described.

HARRY L. STILES.
